UNITED STATES PATENT OFFICE.

CHARLES C. DARLING, OF PROVIDENCE, RHODE ISLAND.

DESIGN FOR A BADGE.

SPECIFICATION forming part of Design No. 27,817, dated November 9, 1897.

Application filed September 17, 1897. Serial No. 652,078. Term of patent 7 years.

To all whom it may concern:

Be it known that I, CHARLES C. DARLING, a citizen of the United States, residing at Providence, in the State of Rhode Island, have invented and produced a new and original Design for a Badge, Button, or Charm, of which the following is a specification, reference being had to the accompanying drawing.

The figure represents a view of the front plate of a badge, pin, or charm, showing my new and original design.

One of the leading features of my design consists in the representation of a log and a pendent leaf extending downward from the log, with the representation of a bird above the leaf in front of the log.

Another leading feature of my design consists in the representation of a leaf having centrally arranged thereon the representation of a globe marked with meridian-lines and parallels of latitude, and having in front of the globe the representation of the stump of a felled tree, with an ax struck in the top of the stump and a cant-hook leaning against the stump at one side, and an ox-yoke at the opposite side.

In the accompanying drawing, A is the representation of a log, which is shown in an inclined position, but which, if preferred, may be shown in a horizontal position.

B is the representation of a bird, arranged in front of the log A, and preferably shown with a branch C in its bill.

D is the representation of a leaf, extending downward from the log A and having at its central portion the representation of a globe E, provided with the represented meridian-lines *a* and parallels of latitude *b*. The representation of the stump F of a felled tree is arranged in front of the lower portion of the globe E, the representation of an ax G being shown as having its blade struck into the top of the stump. A cant-hook H is shown in an inclined position at one side of the stump and an ox-yoke I at the opposite side.

I claim—

The design for a badge, button, or charm, substantially as herein shown and described.

CHARLES C. DARLING.
